PRICE CARD HOLDER

Charles F. Hoofer, Chicago, Ill.

Application December 27, 1932. Serial No. 648,863

8 Claims. (Cl. 40—11)

My invention relates to displaying devices, and has among its objects and advantages the provision of an improved price card holder.

In the accompanying drawings:

5 Figure 1 is a front elevation of my holder showing a price card associated therewith;

Figure 2 is a front elevation with the price card removed;

10 Figure 3 is a view showing the clip portion detached and mounted upon a shelf;

Figure 4 is a top plan view;

Figure 5 is a sectional view taken along the line 5—5 of Figure 1;

Figure 6 is a rear view;

15 Figure 7 is a sectional view taken along the line 7—7 of Figure 6;

Figure 8 is a sectional view taken along the line 8—8 of Figure 6;

Figure 9 is a front elevation of a different form 20 of card holder;

Figure 10 is a sectional view taken along the line 10—10 of Figure 9;

Figure 11 is a top plan view of Figure 10 with a small part removed; and

25 Figure 12 is a front elevation of another form.

In the embodiment selected to illustrate my invention, I make use of a card holding member 10 designed to be detachably connected with a clip structure 12 having shelf-engaging flanges

30 14 and 16. Each part of the device comprises a single piece of sheet metal. The shelf-engaging flanges may be inclined in the direction of each other to provide compensation for shelves of varying thickness, in addition to increasing the frictional relation between the flanges and the shelf.

35 The frame 10 is cut out at 18 and 20 and has its edges shaped to provide a rounded frame 22 surrounding a price card 24. The frames may be enameled or otherwise finished to pro-

40 vide an ornamental appearance.

Referring to Figure 6, it will be noted that the ends of the price card 24 are inserted in the openings 18 and 20, at which time the ends of the card are positioned behind the vertical stretches 45 of the frame 22. These stretches hold the card firmly against the backing plate 26 comprising a portion of the sheet metal from which the frame is made. The price card is of such width that its horizontal edges lie contiguous to the horizontal

50 stretches of the frame, thus enhancing the ornamental appearance of the assembled parts.

The clip structure 12 is provided with two tongues 28 arranged substantially in alignment with the plate 30 connecting the flanges 14 and

55 16. This plate lies snugly against the edge of

the shelf 32 when the clip is mounted thereon. A pair of ears 34 is formed integrally with the backing plate 26 and arranged for connection with the tongues 28 to detachably mount the card holding member 10 to the clip structure. 60

The card holding member is connected with the clip by passing the tongues 28 under the ears 34 and sliding the plate inwardly of the tongues. I have offset the ears 34 slightly with respect to the backing plate 26, so that the tongues 28 will be positioned in a plane common to the backing plate. When the card holding member 10 is pushed home, the upper edge of the frame will be slightly below the upper surface of the shelf 32. This arrangement provides a minimum of 70 obstruction against the removal of cans or packages from the shelf.

When the two parts of the device are assembled, the plate 30 is arranged in frictional engagement with the backing plate 26. The tongues 28 75 in being positioned substantially in a common plane with the plate 30 cause a binding action between the tongues 28 and the ears 34 and between the plate 30 and the backing plate 26, so that the card holding part is held firmly in assembly with the clip structure. The parts are arranged so that the frame is associated with the clip structure by a simple sliding movement. I have provided an opening 36 in the backing plate 26 to facilitate removal of the card 34. 80

The card holding frame in being detachable from the clip part permits the latter to remain permanently upon the shelf. This eliminates any difficulty experienced in putting the clips on the shelves and eliminates any scratching or 90 marring of the finish on the shelf. The clip structure projects above and below the shelf distances equal to the thickness of the portions 14 and 16 so that there is very little obstruction to the removal of goods from the shelf. A quantity 95 of card holding members 10 may be provided with price cards of different denominations and kept in stock ready for use. These parts stack firmly in nested relation, and the cards are protected from becoming damaged. 100

In Figures 9, 10, and 11, I have illustrated another form in which the card-holding member 38 is identical with the member 10 with the exception that the edges of the backing plate 40 are slit at 42 and the tabs 44 bent out of alignment with the backing plate to provide retaining lugs 46. In this form the clip structure comprises a single piece of wire bent to provide shelf engaging loop portions 48 and 50. These portions are connected together by straight reaches 52 of the 110

wire arranged to lie adjacent the backing plate 40 and under the lugs 46. I have shown the loops 48 and 50 as being arranged in converging relation to provide compensation for variations in 5 shelf dimensions. The clip structure is connected with the frame part 38 by inserting one of the reaches 52 under one of the lugs 46 and expanding the loop portions sufficiently far to permit the other reach 52 to be passed under the other lug 46. The wire is sufficiently resilient to permit the connection to be easily made, and the tension of the wire holds the two parts in firm assembly. It will be noted in referring to Figure 10 that the flanges 54 are bent back slightly beyond 10 the back side of the backing plate 40 to provide abutments preventing movement of either part 15 relatively to the other longitudinally of the reaches 52.

The wire clip part may be easily formed by 20 simple bending operations, which cuts down the cost of the article. The loops 48 and 50 in being shaped of wire, have smooth round surfaces which make the clip easy to mount upon a shelf with no cutting or scratching of the finish. A wire construction also provides a resiliency which is not destroyed by bending of the parts. The sheet metal clip may be flexed within reasonable limits, but bending frequently causes the parts to 25 assume new shapes, which is not true of a spring 30 construction.

The structure in Figure 12 differs from that illustrated in Figures 9 to 11, inclusive, in that the backing plate 56 is provided with four slits 58 in each of its vertical edges, to permit two 35 lugs 60 to be formed in each edge. These lugs are offset in the same way as the lugs 46. The tabs 62 remain in their original planes common to the backing plate. The tabs 62 function as abutments for the stretches 52. Referring to Figure 9, 40 it will be noted that the ends of the wire from which the clip part is formed are arranged in abutting relation at 64. The ends of the wire need not be connected together. I have arranged the tab 62 in such a manner that the abutting 45 ends of the wire will be positioned directly behind one of the tabs, which results in tying the ends together. The stretches 52 are also supported against buckling when the shelf engaging portions 48 and 50 are pressed together or apart.

Both clip parts are shown as having the bottom 50 shelf-gripping portion shorter than the upper part. This construction provides a pull upon the clip part when it is assembled upon the shelf tending to hold the clip in its final adjusted position thereon.

Without further elaboration, the foregoing will 55 so fully explain my invention that others may, by applying current knowledge, readily adapt the same for use under various conditions of service.

I claim:

1. The combination with a clip having means 60 for connection with a shelf, of a card holding frame having a pair of spaced openings for receiving the ends of a card, the material between said openings providing a backing plate for the card, said backing plate being provided with means arranged for detachable connection with said clip.

2. The combination with a clip having means 70 for connection with a shelf, of a card holding

frame having a pair of spaced openings for receiving the ends of a price card, the material between said openings comprising a backing plate for the price card, lugs carried by said backing plate, and means comprising portions of said clip arranged for detachable connection with said lugs. 80

3. The combination with a clip having a pair of wire loops for frictionally engaging a shelf and a pair of wire reaches connecting said loops, of a card holding frame having openings to receive the ends of a price card, the material between said openings providing a backing plate for the price card, said backing plate having a pair of lugs shaped to detachably receive said reaches. 85 90

4. A price card holder comprising a clip having two flanges arranged for frictional engagement with a supporting shelf, a plate connecting said two flanges, a pair of tongues associated with one of said flanges, a frame, said frame having a pair of price card holding openings and a backing plate, and ears formed integrally with said backing plate, said ears being offset slightly with respect to the backing plate and arranged to 100 frictionally engage said tongues to permit the frame to be detachably connected with the clip, said plate being held firmly against said backing plate. 105

5. The combination of a wire clip bent to provide a pair of shelf engaging parts and a pair of reaches connecting said parts, a card holding frame having openings to receive the ends of a price card, the material between said openings comprising a backing plate, and lugs carried by 110 said backing plate, said shelf engaging parts being arranged to be flexed to permit the reaches to pass between the lugs and the backing plate, the tension of the wire forming said shelf engaging parts holding the clip and the card holding frame in firm assembly. 115

6. A device of the type described comprising a clip arranged for frictional engagement with a shelf, a card holding part comprising a metal plate having openings at two ends to receive the 120 ends of a price card, the marginal edges of said plate being shaped to provide a curved frame surrounding said price card, and means carried by said card holding part for detachable connection with said clip. 125

7. The combination with a wire clip having a pair of loops for frictionally engaging a shelf and a pair of reaches connecting said loops, of a card holding frame, and lugs carried by said card holding frame and arranged for engaging 130 said reaches to hold the frame in assembly with the clip.

8. The combination with a wire clip having a pair of loops for frictionally engaging a shelf and a pair of reaches connecting said loops, of a card holding frame having openings to receive the ends of a price card, the material between said openings providing a backing plate for the price card, said backing plate being provided with slits adjacent said openings, the material between said slits being offset with respect to the backing plate to provide lugs for engaging said reaches, to detachably connect the frame with the clip. 135 140
